UNITED STATES PATENT OFFICE.

STILLMAN THORP, OF PORTLAND, AND WESLEY THORP, OF TURNER, MAINE.

BOOT-HEEL.

Specification of Letters Patent No. 22,755, dated January 25, 1859.

To all whom it may concern:

Be it known that we, **STILLMAN THORP**, of Portland, in the county of Cumberland, and **WESLEY THORP**, of Turner, in the county of Androscoggin, State of Maine, have invented a new and useful Improvement in Boots and Shoes; and we do hereby declare that the same is fully described and represented in the following specification and the accompanying drawings, of which—

Figure 1, denotes a top view of the heel and shank of the outer sole of a boot having our invention applied to them, while Fig. 2, is a bottom view, Fig. 3, a side elevation, and Fig. 4, a longitudinal section of the same.

In such drawings A, exhibits the heel and B, the outer part of the sole of the shank portion of a boot or shoe the latter having a metallic spring or elastic stiffener, C, laid on the upper surface of the same and so as to extend between it and the insole and from the upper end of a screw pin or bolt D, which extends down through the middle of the heel and carries a circular lift or plate of metal E, which is screwed on it and not only serves as a screw nut but as a rotary heel. Furthermore, the shank stiffener combined with the rotary heel plate E, by means as described is firmly supported by it, and such means under the movements imparted to such shank stiffener by the foot of a person while in the act of walking; and besides this the stiffener constitutes a firm support

for the holder of the rotary heel piece, 35 When the rotary heel piece becomes worn on one side more than another it may be turned around on its screw pin or holder, so as to bring a fresh or thick part in the place of the worn portion. In this way the durability of the heel may be protracted. By the conjoint action of the shank stiffener and the rotary heel piece connected together as described the lifts i, i, i, of leather composing the heel are confined closely together. 45

If desirable, a leather, india rubber or gutta percha lift may be applied to the outer surface or side of the metallic heel piece.

We do not claim an elastic metallic spring 50 or plate applied in the shank of a boot; nor do we claim a rotary heel piece applied separately from the metallic shank piece, as we are aware that neither is new; but

What we do claim is—

The combination of the metallic plate 55 spring or shank stiffener and the rotary heel piece connected together and applied to the heel and shank of a boot or shoe substantially as specified.

In testimony whereof we have hereunto set our signatures.

STILLMAN THORP,
WESLEY THORP.
